UNITED STATES PATENT OFFICE.

JOSEPH S. SEIBERT, OF PULLMAN, ILLINOIS.

METALLURGIC GAS-FURNACE.

SPECIFICATION forming part of Letters Patent No. 315,846, dated April 14, 1885.

Application filed September 6, 1884. (No model.)

To all whom it may concern:

Be it known that I, JOSEPH S. SEIBERT, a citizen of the United States, residing at Pullman, in the county of Cook and State of Illinois, have invented certain new and useful Improvements in Metallurgic Gas-Furnaces for Puddling, Heating, and Treating Iron, of which the following is a specification, reference being had to the accompanying drawings, in which—

Figure 1 is a vertical longitudinal section of my improved furnace on the line $n n$ of Fig. 2. Fig. 2 is a front elevation of the gas-producer and gas-chamber. Fig. 3 is a vertical cross-section through the gas-producer and gas-chamber on line $x x$ of Fig. 1. Fig. 4 is a horizontal section through the gas-producer, combustion-chamber, and gas-chamber on line $z z$ of Fig. 1. Fig. 5 is a vertical cross-section through the furnace and furnace-bed on line $y y$ of Fig. 1, showing the ports of the gas and air flues coming from the gas-chamber and hot-air grate.

Like letters refer to like parts wherever they occur.

My invention relates to improvements in the construction of that class of furnaces known as "metallurgic gas-furnaces," and it consists in arranging the gas and air flues of the furnace so that it can either be used as a gas-furnace proper or a direct-draft furnace, as will be more fully hereinafter specified, and specifically pointed out in the claims.

To accomplish the above ends my invention is illustrated in details of construction hereinafter more specifically set forth.

I will now proceed to describe my invention so that others skilled in the art and manufacture to which it appertains may apply the same.

In the annexed drawings, A A A represent the gas-producer, over which spans the arch D, provided with flues a a a a a. Said flues open alternately on the side of arch D, at points h and h respectively, admitting the gas and leading it down through one side wall of the producer to a small chamber, b, from where it passes to the main gas-chamber C. The gas-producer A is provided with grate-bars i, resting over the ash-pit E, which latter is provided with doors K, having spy-glasses s and poke-holes p, as shown in Fig. 2 of the

annexed drawings. The extension F of ash-pit E is again covered by means of doors or plates m at the level of the ground.

To operate the gas-producer, steam is introduced under the grate-bars i through a steam-blast pipe, l, which after entering the ash-pit E forms a square frame, j, near the wall thereof, and contains on the upper side numerous small tubes or injectors wherethrough the steam is forced between the grate-bars i into the burning fuel. Thus the production of gas is greatly increased.

The front wall of the gas-producer A is provided with a working-door, K', having a spy-hole, s', and two poke-holes, p'. A hopper, H, with the bottom end extending through the wall, is placed on each side of door K', said hopper H being provided with a sliding bottom nearest to the wall, and a hinged cover, q.

In charging the producer with fuel the hopper H is filled with coal and closed with cover q. The bottom of the hopper is then raised by means of lever r, allowing the fuel to slide on an inclined plane through the opening in the wall onto the grate-bars i.

Directly under the hopper H poke-holes p" are placed for the purpose of facilitating the even spreading of the fuel over the fire-grate.

The rear wall of gas-producer A, dividing it from the combustion-chamber B, has an arch-shaped opening, O, communicating thus with the said chamber B. Said wall, and on each side of the opening O, contains a number of air-flues, e e e, leading from the top of the furnace to the fire-place of the hot-air producer B. These flues are closed from the top with cover f, operated with levers from the side of the furnace.

Behind the combustion-chamber B is located the gas-receptacle g, to which gas is admitted from the gas-chamber C through the damper d, as shown in Figs. 1 and 4. Hot-air flues t pass from the combustion-chamber B into the furnace L and alongside the gas-flues g, in the manner shown in Fig. 5.

The furnace L contains the usual furnace-bed, M, and is provided at one side with three or more working-doors, u u u. The gas, after rendering its heat and passing through the furnace, is let off through the neck T, provided with damper W, into the stack.

The gas-chamber C is provided with an im-

proved soot-screen, I, which is placed before the damper d, and can be either pushed across the gas-chamber C or removed to its receptacle R, as required. Gas-chambers b and C are 5 each provided at their front ends with doors to enable the removal of soot.

In operating my furnace as a gas-furnace proper the opening O between the gas-producer A and the combustion-chamber B should 10 be closed and the damper d in the gas-chamber C opened, thus allowing the gas to pass through the soot-screen I to the gas-receptacle g, from where it enters into the furnace L, igniting and mixing therein with the hot air 15 coming from chamber B through the hot-air ports t. During this operation damper f over the air-flues e e e should be left open.

A direct-draft furnace is formed by closing damper d in gas-chamber C and allowing the 20 gas from the producer A to pass through the opening O into the chamber B, igniting therein and passing with the hot air through the hot-air ports t only into the furnace L. During this operation damper f over the air-flues e e e 25 should be closed.

A further advantage in operating my furnace consists in the continuous production of heat, at the same time allowing the burning out of the soot in the gas-chambers b and C by 30 opening the doors K K, igniting the gas in the producer A at once, and thus entering the furnace L as a flame. The damper f being closed and the exit at the neck T of the furnace L being regulated by means of damper W, the heat is retained and utilized to advantage in the furnace. I also point out the easy 35 access to the gas and hot-air flues g and t, in repairing the same, from the side of the hot-air grate without disturbing any brick-work 40 in the side wall or arches of the furnace.

Having thus described my invention and its operation, what I claim, and desire to secure by Letters Patent, is—

1. The combination of the gas-producing chamber A, combustion-chamber B, separated 45 by a wall having a communicating opening therein, the gas-receptacle g, gas-chamber C, and damper d, substantially as described, and for the purposes set forth.

2. The combination of the gas-producing 50 chamber A, the arch D, provided with flues a, said flues opening alternately in the sides of the arch, and chambers b and C, substantially as described, and for the purposes set forth.

3. The combination of the gas producing 55 chamber A, the arch D, provided with flues a, said flues opening alternately in the sides of the arch, and the chambers b C, provided with doors for the removal of soot, substantially as described, and for the purposes set forth.

4. The combination of the gas-producing 60 chamber A, the arch D, provided with flues a, the chambers b and C, and screen I, located 65 in receptacle R, whereby the screen may be placed across the chamber C or retained in the receptacle, as specified.

5. The combination of the gas-producing 70 chamber A, arch D, provided with flues a, the chambers b C, damper d, and gas-receptacle g, substantially as described, and for the purposes set forth.

6. The combination of the gas-producing 75 chamber A, arch D, provided with flues a, the rear flues, e, having cover f, the chambers b C, gas-receptacle g, furnace L, and combustion-chamber B, having ports t, substantially as described, and for the purposes set forth.

In testimony whereof I affix my signature in 80 presence of two witnesses.

JOSEPH S. SEIBERT.
